United States Patent Office.

J. M. WATSON, OF SHARON, MASSACHUSETTS.

Letters Patent No. 97,259, dated November 23, 1869.

IMPROVEMENT IN PLANT-PROTECTORS.

The Schedule referred to in these Letters Patent and making part of the same.

Be it known that I, J. M. WATSON, of Sharon, in the county of Norfolk, and State of Massachusetts, have made an invention of a new and useful "Plant-Protector," or the supporting-frame or skeleton of such protector; and do hereby declare that the following is a description thereof, taken in connection with the accompanying drawings, which form a part of this specification, in which—

Figure 1 is a perspective representation of the frame of a plant-protector, as folded or contracted into a reduced bulk for transportation or stowage.

Figure 2 is a like representation of my invention, in an open or extended state, and ready for use.

The purpose of this invention is to produce a plant-protector, which shall secure simplicity, extreme low cost of production, and effectiveness and durability in use.

I secure this result by the employment of a horizontal hoop, as the chief support or basis of the device and of the two bow-shaped or arched standards or supports for upholding the gauze netting, the bows being so pivoted to each other at their centres, and one of them pivoted adjustably, at or near its extremities, to the inner periphery of the hoop, that both may be folded or contracted concentrically within the area described by the circumscribing hoop, or as represented in fig. 1 of the accompanying drawings.

These drawings exhibit, at *a*, a thin annular hoop, composed of wood or any suitable substance, and made substantially in the form of an ordinary barrel-hoop, while *b* denotes a clasp or bow, composed of a flat strip of similar material, such bow, when elevated, spanning the hoop, as represented in fig. 2 of the drawings.

Each side of the bow or clasp *b*, in immediate proximity to the hoop *a*, is provided with a slot, *c* or *c'*, while, extending through this slot and the hoop, and overlapping the bow, is a screw or bolt, *d* or *d'*, the portion of each leg of the bow below the hoop serving, by being forced into the earth, as a means of support to the device.

The utility of the slots will be apparent when it is observed that they extend beyond the centre from which the arc of the hoop is struck, since, were it not for these slots, a semicircular bow only would be permitted to rise above the hoop, owing to the fact, that as the bow must be folded or turned within the hoop, it necessarily cannot exceed a semicircle between its turning-point and largest radius.

The slots *c* *c'*, while permitting the bow to be lowered within the hoop, also allow it, when erected, to acquire a much greater altitude than would otherwise be the case.

To the inside of the bow *b*, I apply a second bow, or support, *e*, of like size, shape, and material, the two being pivoted together at their centres, as shown at *a'*, but the latter being otherwise disconnected with the hoop.

The legs of this last-mentioned bow serve, in connection with those of the bow *b*, as supports to sustain the device in place upon the ground.

To contract or reduce the bulk of the device thus made, the inner bow *e* is to be turned upon the pivot to the extent of one hundred and eighty degrees, which brings it into alignment with the bow *b*.

The two bows are then to be lowered vertically with respect to the hoop *a*, until the upper boundaries of the slots *c* *c'* bring up against the pins or bolts *d* *d'*, which thus become pivots, to allow the two bows to be turned together from a perpendicular position to a horizontal one within the hoop, or as shown in fig. 1 of the accompanying drawings. The implement, in this contracted condition, occupies very little space—a fact which, in many instances, becomes one of importance.

As it is believed that the reader, from the above explanation, will readily understand the unfolding of the bows, further elucidation upon this point is not given.

It is not my intention to attach the gauze netting or covering to the hoop in a permanent manner, but to secure it thereto by an elastic loop, as shown in the drawing, which contracts about it with sufficient tenacity to retain it securely in place.

This mode of applying the gauze covering, then, constitutes one of the peculiar characteristics of my invention.

The advantages of this mode of applying the gauze covering are several: It economizes time, both in applying the original covering or in renewing an old one, which frequently becomes necessary. The cost of the gauze covering or netting is considerably greater, more than double that of the skeleton frame. This fact often deters manufacturers from accumulating a quantity of plant-protectors to be carried through the winter, owing to the uncertainty of the demand in the ensuing spring. Owing to my mode of manufacture, this objection is to a great extent overcome.

The frame may be manufactured and sold to produce-raisers or to dealers, with or without the gauze, which may be purchased and applied as occasion demands.

Claim.

I claim—

1. A plant-protector frame, composed of the hoop *a*, and bows *b* and *e*, such bows being pivoted together, and the former pivoted to the hoop, and the whole being combined and operating as explained.
2. In combination with the above, the gauze covering, or shield, and the elastic band or loop, the whole arranged and operating substantially as described.

J. M. WATSON.
